UNITED STATES PATENT OFFICE.

GEORGE R. MARTZ, OF DALLAS, TEXAS.

TOOTHBRUSH.

1,334,770.

Specification of Letters Patent. Patented Mar. 23, 1920.

Application filed September 29, 1919. Serial No. 327,090.

To all whom it may concern:

Be it known that I, GEORGE R. MARTZ, a citizen of the United States, residing at Dallas, in the county of Dallas and State 5 of Texas, have invented certain new and useful Improvements in Toothbrushes, of which the following is a specification.

This invention relates to new and useful improvements in tooth brushes.

10 The object of the invention is to provide a tooth brush that will penetrate the interstices between the teeth and remove the debris therefrom by a vertical movement of the bristles and do so without discomfort, 15 and a brush that is sanitary and convenient for being carried in a pocket in the clothing or in a traveling bag.

In carrying out the invention I use a handle having a longitudinally extending 20 passage through its entire length to receive a plunger having a spiral groove extending along part of the length of same, the said handle assuming the relation of a housing to the plunger. The nongrooved end of 25 the plunger protrudes from the end of the handle through an aperture in a removable retaining member and terminates in a thumb ring integral thereto, the said retaining member engaging a collar on the plunger. A cylindric support integral with the 30 opposite end of the handle receives a rotatable cylindric brush, the said brush having a trunnion at its outer end which engages in a socket in the inner surface of the head 35 of the cylindric support and a longitudinal bore extending through the greater portion of the core of the said brush adjacent the center of the core, the plunger entering the said bore from the inner end of the brush 40 and retaining the brush in the support. By operating the plunger longitudinally of the handle the brush is caused to rotate by means of an inwardly protruding pin within the bore in the core of the same which 45 engages in the spiral groove in the plunger.

When in operation the brush is partially exposed by a longitudinally disposed opening in one side of the cylindric support, the support covering that portion of the brush 50 which does not engage the teeth, and when not in operation the brush may be inclosed by means of a slide so disposed as to cover the said opening. The plunger may be removed from the handle by removing the retaining member and thereby releasing the brush which may be removed from the sup-

port and sterilized or replaced by a new brush.

The invention will be more readily understood from a reading of the following 60 specification and by reference to the accompanying drawings, in which an example of the invention is shown, and wherein:

Figure 1 is a side elevation showing the handle in section of tooth brush constructed 65 in accordance with this invention,

Fig. 2 is a cross-sectional view of the brush with the slide open,

Fig. 3 is a cross-sectional view of the brush with the slide closed, and 70

Fig. 4 is a sectional view of the brush.

In the drawings the numeral 5 designates a cylindric support having a handle 6 integral therewith, the said handle having a longitudinally disposed passage 7 extending 75 through its entire length and receiving a plunger 8 having a spiral groove 9 extending along part of its length. A cylindric rotatable brush 10 having a longitudinally disposed bore 11 extending the major portion 80 of the length of the core 12. The said brush is retained within the cylindric support at the outer end by means of a trunnion 13 engaging within a socket 14 in the inner surface of the head of the cylindric 85 support and at the inner end by the plunger engaging in the bore in the core of the brush, the plunger being retained in engagement in the bore by means of a collar 15 integral with the plunger which engages 90 a removable retaining member 16 adjacent the termination of the handle.

The plunger protrudes from the end of the handle through an aperture in the retaining member and terminates in a thumb ring 17 by means of which it may be operated longitudinally of the handle. An inwardly protruding pin 18 within the bore 95 in the core of the brush engages within the spiral groove extending along the plunger 100 and causes the brush to rotate transversely of the handle when the plunger is operated.

The cylindric support has a longitudinally disposed opening 19 extending along one side of the same which exposes the portion 105 of the brush engaging the teeth, the support serving to shroud the portion of the brush which does not engage the teeth and thereby precluding the laceration of the mucous membrane.

By rotating a cylindric brush transversely of a handle when the said handle is held in

- a horizontal position, a vertical movement of the bristles is effected, and by exposing that portion of the brush which engages the teeth and shrouding the portion not engaging the teeth to preclude the laceration of the mucous membrane, the teeth may be thoroughly cleansed with ease and comfort, all waste matter being removed from between the teeth.
- 10 The brush 10 may be completely incased within the cylindric support 5 by means of a slidable cover 20 engaging the support in such a manner as to be movable into such a position as to close the opening 19. The 15 said cover being retained in engagement with the support by means of an immovably projecting flange 21 which engages in a transverse groove 22 adjacent the inward end of the support.
- 20 A reciprocating spiral spring 23 disposed within the passage 7 and surrounding the plunger 8 assists in the operation of the said plunger by engaging the collar 15 and shoulders 24 occurring within the passage, 25 thereby returning the plunger to a withdrawn position when it is released after having been pressed. An outwardly protruding collar 6' integral with the handle 6 enables the brush to be more easily held.
- 30 By removing the retaining member 16 the plunger is released and may be withdrawn from the handle; thereby releasing the brush and permitting the latter to be removed from the support and sterilized or a 35 new brush supplied.

It will be noted that a brush constructed

in accordance with this invention is sanitary and convenient for being carried.

What I claim, is:

1. In a tooth brush, a cylindric support, 40 a removable rotatable brush within the support, a handle member integral with the support, a finger pressed spiral plunger disposed within the handle member and engaging within the brush for rotating the 45 brush and retaining the brush within the support, the said handle member assuming the relation of a housing to the plunger, an operating means between the plunger and the handle member, and means for removing the plunger from the handle member. 50
2. In a tooth brush, a cylindric support, a cylindric rotatable brush having a core and a longitudinally disposed bore through 55 the core, an inwardly protruding pin within the bore, a handle member integral with the support, a finger pressed spiral plunger longitudinally disposed within the handle member and engaging the pin so as to rotate 60 the brush when operated, a reciprocating spring between the plunger and the handle member, an opening in the cylindric support for exposing that portion of the brush engaging the teeth, removable means for 65 retaining the plunger within the handle member, means for removing the plunger from the handle member, and means for removing the brush from the support. 70

In testimony whereof I affix my signature. 70

GEORGE R. MARTZ.
